UNITED STATES PATENT OFFICE.

JOHN T. H. DEMPSTER, OF SCHENECTADY, NEW YORK, ASSIGNOR TO GENERAL ELECTRIC COMPANY, A CORPORATION OF NEW YORK.

VAPOR ELECTRIC APPARATUS.

1,091,564.

Specification of Letters Patent. Patented Mar. 31, 1914.

Application filed April 4, 1904. Serial No. 201,487.

To all whom it may concern:

Be it known that I, JOHN T. H. DEMPSTER, a citizen of the United States, residing at Schenectady, in the county of Schenectady and State of New York, have invented certain new and useful Improvements in Vapor Electric Apparatus, of which the following is a specification.

My present invention relates to improvements in the construction and operation of vapor electric apparatus, such, for example, as vapor-lamps, rectifiers or the like.

More especially my invention comprises certain improvements relating to the starting of apparatus of the types mentioned.

The features of novelty characteristic of my invention I have pointed out with particularity in the appended claims. The invention itself, however, both as concerns the details of construction and the mode of operation will be better understood by reference to the following description taken in connection with the accompanying drawings, in which—

Figure 1 illustrates one embodiment of my invention and Fig. 2 a modification.

Fig. 1 illustrates the application of my invention to a mercury vapor lamp. The lamp shown is one which operates normally with the tube or exhausted envelop in an inclined position. The envelop is indicated at 1 and may be of glass or other suitable material. At the top the envelop is enlarged to form a condensing chamber 2, the bottom portion of which constitutes a pocket for containing a body of mercury 3, constituting one of the main electrodes of the lamp. The leading-in conductor 4 provides for making electrical connection with this electrode. At the bottom of the tube 1 a body of mercury 5 constitutes the other main electrode of the lamp. This body of mercury is contained within a small cup-shaped chamber, the walls 6 of which separate the mercury from the outer annular body of mercury 7 constituting a starting electrode. The walls 6 which separate the two bodies of mercury may be formed of glass, fused quartz or any other suitable insulating material. To each of these bodies of mercury 5 and 7 current may be conveyed by leading-in conductors 8 and 9 respectively. Placed at intervals, more or less regular, along the under side of the tube 1 are a number of pockets 10, 11 and 12 con-

taining bodies of mercury 13, 14 and 15, which constitute auxiliary electrodes to assist in the starting of the main arc in the lamp. Electrical connection with these starting electrodes is effected in the usual manner by means of suitable leading-in conductors 16, 17 and 18. All of the electrodes 7, 13, 14, 12 and 3 are electrically connected together and to the supply conductor 19 through the medium of interposed resistances as at 20, 21, 22 and 23.

A variety of means may be employed to produce the initial starting arc in the lamp. Thus, for example, the tube may be shaken or oscillated so as to cause a momentary flow of mercury over the barrier or walls 6 separating the electrodes 7 and 8. The electrical connection thus afforded completes a circuit from the supply lead through the series of resistances 20 to 23 inclusive to the other supply lead 24. As soon as this engagement between the two mercury bodies is broken, as the mercury again assumes a position of equilibrium, an arc is produced. If the polarities be such that the electrode 5 is of negative polarity the electrode becomes a cathode and the initial arc then extends up the tube to the electrode 13 and then successively from the electrodes 14 and 12 to the main anode 3. This movement of the arc up the tube is caused by the presence of the resistances 20 to 23 inclusive which offer to the current from the main 19 a higher resistance path than is afforded by the arc path in the tube from the various positive electrodes to the negative.

Instead of shaking the tube to form the initial arc I may make use of an inductive discharge produced, for example, by means of the inductance coil 25. At starting, the switch 26 is closed and is then suddenly opened. The inductive kick thus produced causes a high-potential spark to jump between the two electrodes 7 and 5 which spark is then followed by a current from the main source and this in turn by a progression of the arc up the tube to the main electrode 3. Another means for starting the arc in a tube provided with multiple starting electrodes is shown in Fig. 2. The exhausted envelop of this lamp is indicated at 27 and is mounted in some convenient way so that it may be tilted or its inclination varied. For this purpose one end may be suspended by a

cord 28 and the other end by a cord 29 passing for convenience over a pulley 30. At opposite ends of the tubes are formed pockets containing respectively bodies of mercury 31 and 32 constituting the main electrodes of the lamp. At intervals in the length of the lamp, a number of pockets are located on the under side of the tube as indicated at 33, 34, 35 and 36. These pockets contain bodies 10 of mercury 37, 38, 39 and 40 connected as before by means of suitable leading-in conductors to a resistance circuit and to the upper electrode 32 as indicated. The resistances separating the connections between 15 the electrodes are connected at 41, 42, 43 and 44.

In order to start the lamp the cord running over the pulley 30 may be slackened so as to lower the end of the lamp supported 20 thereby and thus cause mercury from the electrode 31 to flow to the adjacent starting electrode 37 and thence on down the tube from one starting electrode to another. Ordinarily it is sufficient to cause a bridging 25 stream of mercury to flow from the electrode 31 to the electrode 37 and then break, whereupon the arc produced will jump successively from one starting electrode to another until it reaches electrode 32. If the arc does not 30 start up immediately throughout the length of the tube the flow of mercury may be continued from the electrode 37 on down the tube until the lamp is in normal operation. The cord 29 may then be pulled to the position 35 illustrated in the drawings.

One advantage of the construction illustrated is that but very little mercury is re-

quired to produce the starting arc. This advantage is of considerable value in the case of long tubes where a great deal of mercury would be required if it were attempted to produce an unbroken stream from one end of the tube to the other.

It will be evident to one skilled in the art that numerous modifications may be made 45 in the structural modification of my invention, for which reason I do not wish to be limited to the exact details shown and described.

What I claim as new and desire to secure 50 by Letters Patent of the United States, is,

1. The combination of an exhausted envelop, fluid electrodes located respectively in opposite ends of the envelop, and a plurality of coöperating fluid starting electrodes 55 of the same polarity.

2. The combination of an envelop, main electrodes therefor, intermediate electrodes all of the same polarity electrically connected with each other, and means for causing a flow of mercury from one main electrode to one or more intermediate electrodes.

3. The combination of an exhausted envelop, normally inclined, main electrodes for said envelop, and intermediate electrodes of one polarity consisting of bodies of fluid located respectively in a series of pockets arranged between said main electrodes.

In witness whereof, I have hereunto set my hand this first day of April, 1904.

JOHN T. H. DEMPSTER.
